COMBINATION AUTOMOBILE SUN VISOR AND SHADE

Mary I. Anderson, 14206 N. 95th St.,
Longmont, Colo. 80501

Filed Apr. 14, 1969, Ser. No. 16,735

Term of patent 14 years

Int. Cl. D12—14

U.S. Cl. D14—6

FIG. 1.

FIG. 5.

FIG. 2.

FIG. 3.

FIG. 4.

FIGURE 1 is a front elevational view showing my combination automobile sun visor and shade;

FIGURE 2 is a rear elevation thereof;

FIGURE 3 is a top plan view thereof;

FIGURE 4 is a side elevation of the left side of FIGURE 3; and,

FIGURE 5 is a cross-sectional view along line 5—5 of FIGURE 1, partly broken away to conserve space.

I claim:

The ornamental design for a combination automobile sun visor and shade, as shown.
